UNITED STATES PATENT OFFICE

FRANCIS DE MARINIS, OF BROOKLYN, NEW YORK.

BALLOON CONSTRUCTION.

1,829,584.

Specification of Letters Patent.

Patented Feb. 8, 1920.

Application filed April 14, 1919. Serial No. 230,072.

To all whom it may concern:

Be it known that I, FRANCIS DE MARINIS, a subject of the King of Italy, residing at 189 Sackett street, Brooklyn, in the county 5 of Kings and State of New York, have invented new and useful Improvements in Balloon Construction, of which the following is a specification.

My invention relates to means for carrying intelligence through the air, the same being more particularly related to a balloon construction of that type which is wholly dependent for its flight upon the wind by 10 which it is borne.

15 The paramount object of my invention is to provide a balloon construction for carrying messages, despatches, maps and other data in times of war, during a siege, or at other times when the customary methods of 20 transmitting intelligence are not available or cannot be used.

Having the foregoing and additional objects in view, my invention resides in the arrangement, combination and construction 25 of parts as explained in this specification, particularly pointed out in the appended claim, and illustrated in the accompanying drawings, forming a material part of this specification.

30 The figure in the drawing is a view in perspective of a balloon construction made in accordance with my present invention, parts being broken away.

In the drawing, the numeral 1 indicates 35 a gas bag, made of any suitable material, for instance, of pliable silk cloth. In order to render it air-tight, the bag is coated with varnish or equivalent substance in the usual way. This bag is made spherical in form, 40 and is provided with a valve-body 2 having a screw stop-cock 3. The stem 4 of the stop-cock is considerably larger in diameter than that of the bore 5 provided longitudinally through the valve-body; and the relative 45 position of the stop-cock is such that its stem 4 will intercept and cut off, either partially or wholly, accordingly as it is turned, communication through the bore 5. The wall defining the bore 5, in the path of the 50 stem 4 is provided with a conical seat 6, adapted snugly to receive the conical end 7 of the stem.

The bag is enveloped in a hollow globe, 55 made in two hemispherical sections 8 and 9, each of which has its free edge out-turned to provide an annular flange 10. One of these

sections herein shown as section 9, is provided at its axis with a suitable opening (not shown) through which the valve-body 2 projects. When the bag has been placed 60 in the hollow globe, thus made, the flanges 10 are detachably connected by bolt and nut structures 11 and 12, or other equivalent means. The sections 8 and 9 are made of light metal, preferably of aluminum. 65

Attached to the flanges 10 all around, preferably in equi-spaced relation as shown, are a plurality of cords 13, by means of which a circular basket 14, to which the lower ends of the cords are secured, is suspended from the globe. 70

To cause the balloon construction to ascend and to maintain itself during flight, the bag is inflated with any suitable gas. For instance, hydrogen gas or ordinary coal-gas 75 may be employed. The gas, obviously, is introduced into the bag through the bore 5; whereupon the stop-cock is screwed tight against its escape. When the balloon is to travel but a short distance, the stem 4, 80 through a proper manipulation of the stop-cock, is allowed to engage somewhat loosely in its seat 6, so that the gas may escape gradually from the bag permitting the balloon, in consequence, to descend within the time 85 deemed sufficient to enable it to reach the vicinity of its destination. In adjusting the stop-cock for such a journey, the nature of the gas employed, as well as the state and velocity of the wind, must, obviously, be 90 taken into the consideration.

Through the hollow globe, the weight of the basket and its contents is distributed 95 over the surface of the inflated bag. Being made of metal, the globe is adapted to protect the bag from the force of exploding projectiles. As during flight, the balloon structure is continually oscillating, a bullet from a gun is likely to meet the globe at an oblique angle and to be sheared off without penetrating the bag. 100

The messages, despatches, maps or other matter to be delivered, are placed within and secured to the basket 14.

Having thus described my invention, what 105 I claim and desire to secure by Letters Patent is—

In a device of the kind described, the combination of a pliable gas bag of spherical form, a hollow globe encompassing said bag 110 and made up of two hemispherical sections, each section having its free edges bent out-

wardly to form an annular flange and the lower section having an opening, means for connecting said flanges, a valve-body combined with the bag and projecting downwardly through said opening, to provide communication with the interior of the bag, a valve combined with said valve-body and

controlling communication therethrough, and means for suspending a basket from said connected flanges.

19

In testimony whereof I have signed my name to this specification.

FRANCIS DE MARINIS.
